AIR LINE OILER

Filed Nov. 27, 1926

FIG. -2.

INVENTOR.
Charles C. Hansen
BY *Archibald A. Ade*
HIS ATTORNEY.

UNITED STATES PATENT OFFICE.

CHARLES C. HANSEN, OF EASTON, PENNSYLVANIA, ASSIGNOR TO INGERSOLL-BAND COMPANY, OF JERSEY CITY, NEW JERSEY, A CORPORATION OF NEW JERSEY.

AIR-LINE OILER.

Application filed November 27, 1926. Serial No. 151,126.

This invention relates to oiling devices, but more particularly to an air line oiler adapted to be attached to pressure fluid supply lines used for conveying pressure fluid 5 to rock drills and other similar engines.

The objects of the invention are to prevent interruptions in drilling operations for the purpose of introducing lubricant to the drills and to construct a simplified oiling device 10 capable of delivering a uniform and adequate supply of lubricant to the mechanism intended to be lubricated in any of the various positions which the oiling device may occupy in practice.

Other objects will appear hereinafter.

In the drawings in which is illustrated a preferred modification of the invention,

Figure 1 is a longitudinal sectional elevation of an oiler constructed in accordance 20 with the practice of the invention, and

Figure 2 is a transverse view taken through Figure 1 on the line 2—2 looking in the direction of the arrows.

Referring to the drawings, A designates 25 a casing having a threaded aperture B at one end and at its other end an inwardly extending projection C. The interior of the casing A comprises a reservoir D for oil or other suitable lubricant which may be introduced 30 into the casing through a threaded opening E normally sealed by a filler plug F.

In the present instance a plug G is screwed 35 into the threaded aperture B of the casing to form a closure for the reservoir D. The plug G, like the casing A, also has an inwardly extending projection H similar to the projection C of the casing and these projections C and H are provided with passageways J to form a continuation of an air line 40 K screwed in this instance in the outer ends of the passageways J.

The inner ends L of the projections C and H are preferably of smaller diameter than the projections to form bearings for a sleeve 45 O disposed rotatably thereon. The sleeve O is preferably fitted on the ends L in such a manner as to form fluid tight joints between the surfaces of the sleeve O and the projections C and H. The sleeve O thus forms a 50 portion of the passageway J. In order to convey pressure fluid from the passageway J into the reservoir D, a tube P is screwed in

the sleeve O and is preferably of such length that its free end or outlet opening extends to a point near the wall of the casing. 55

To the end that the tube P may at all times be maintained in a vertical position, thus insuring against the immersion of the outlet opening of the tube P in the oil, the sleeve O is provided with a weight Q so that when 60 the casing A rolls from one position to another, the weight Q will tend to rock the sleeve in such a manner that the tube P will always be maintained in the desired vertical position. 65

The oil is in this instance conveyed from the reservoir D through a passage R in the weight Q and one side of the sleeve O and extending to the outermost end of the weight Q. The weight Q is preferably of such length 70 that the inlet opening S of the passage R will at all times occupy a position near the bottom of the reservoir D.

Disposed in the passage R is a pin T adapted to be actuated by the pulsations occurring 75 in the pressure fluid flowing through the passageway J for delivering oil from the reservoir D into the said passageway J. The pin T is preferably of sufficiently smaller diameter than the passage R to form a suitable 80 space U therebetween for the passage of oil through the said passage R. The pin T may be of any suitable and convenient length but is preferably of such length that one end may at all times contact with the wall of the reservoir D and the other end extends well 85 through the passageway J so that a considerable portion thereof will be exposed to the pressure fluid flowing through the said passageway. This is particularly advantageous 90 when heavy oil is used and the supply of oil in the reservoir is nearly exhausted. Under these conditions when the casing is rotated during the course of the work, the oil does not remain level but moves with the casing. By 95 permitting the pin T to bear on the wall of the casing the weight will, to some extent, follow the movement of the casing and maintain the inlet opening S of the passage R in communication with the oil in the reservoir. 100

The operation of the device is as follows: Pressure fluid, such as compressed air, entering the passageway J from the air line K will, by the pulsations caused by the admission and

cut-off of the pressure fluid in the tool to be oiled, cause the pin T to vibrate in a direction transverse to the passage R. At the same time pressure fluid will pass through the tube 5 P and, entering the reservoir D, will create a pressure on the surface of the oil. With the tool or engine at rest the pressures in the reservoir and the passageway will be balanced. However, when the tool is in operation, a state 10 of slight unbalance will be obtained in the pressures in the reservoir and the passageway so that the oil will tend to rise in the passage R, and the pin T, due to its vibratory action, will then force the oil from the passage R into 15 the passage J, from whence it will be carried in the form of vapor to the tool to be oiled by the pressure fluid utilized for operating the tool.

Whenever the air line and thus also the casing A is shifted from one position to the other as is frequently done in drilling and similar operations, the sleeve O will be rocked freely about the projections C and H by the weight Q so that the tube P will at all times be maintained in a vertical position, thus insuring 20 against the admission of oil into the tube P 25

and against the immersion of said tube in the oil.

I claim:

An air line oiler comprising a casing forming an oil reservoir, inwardly extending projections in the casing, said projections being hollow to form a pressure fluid passageway, a sleeve rotatable on the projections forming a portion of the passageway, a tube carried by the sleeve conveying pressure fluid from the passageway into the reservoir, a weight integral with the sleeve adapted to rock the sleeve for maintaining the tube in a vertical position, said sleeve and said weight having a passage opening at the outer end of the weight, and a pin extending loosely through the passage adapted to be actuated by the pulsations occurring in the pressure fluid flowing through the passageway for delivering oil 30 from the reservoir to the passageway, said pin bearing with one end against the wall of the casing to retard rotary movement of the weight relatively to the casing. 35

In testimony whereof I have signed this 40 specification.

CHARLES C. HANSEN.
